Inventor:

Bernard Bartmann

UNITED STATES PATENT OFFICE.

BERNARD BARTMANN, OF MÜNSTER, WESTPHALIA, GERMANY.

BOBBIN-HOLDER.

1,003,026.

Specification of Letters Patent. Patented Sept. 12, 1911.

Application filed April 12, 1911. Serial No. 620,603.

To all whom it may concern:

Be it known that I, BERNARD BARTMANN, a citizen of the German Empire, residing at Münster, Province of Westphalia, Kingdom of Prussia, Germany, have invented certain new and useful Improvements in Bobbin-Holders; and I do hereby declare the following to be a full, clear, and exact description of the invention, such as will enable others skilled in the art to which it appertains to make and use the same.

This invention relates to bobbin-holders for supplying simultaneously in warping machines, twist frames, yarn reels and other like mechanism a number of threads corresponding to the number of bobbin holders, a series of bobbins being mounted on each holder at such angles that their axial lines will intersect at a point beyond them where a thread guide is placed, and the thread passing from one to another of said bobbins throughout the series of each bobbin-holder, a full bobbin being substituted for each empty one as fast as such emptying occurs and the threads connected, that there may be no interruption of supply.

The chief objects of the present invention are to facilitate such substitution and thread connection, to avoid the unnecessary complexity, waste of space and expense of manufacture and to greatly lessen the risk that the thread will be broken.

To these ends the said invention consists in the construction and combination of parts hereinafter more particularly set forth and claimed.

In the accompanying drawings: Figure 1 represents a side elevation of two bobbin-holders and their bobbins embodying my invention, and a part of the frame on which they are mounted, the guide bar of the latter being also shown in detail; Fig. 2 represents an elevation of the same parts taken at right angles to Fig. 1, showing however a smaller part of the frame and only a single bobbin-holder; Fig. 3 represents a detail enlarged view in side elevation of the carriage *e* and integral pivot stud *d*; Fig. 4 represents a similar view of the bottom of *t*; Fig. 5 represents a similar view in side elevation of the hub *t'*, its lower integral prismatic part *t''* and the base bar *t* broken off short; Fig. 6 represents a similar view of the same, the hub *t'* and the prismatic part *t''* being shown in cross section; Fig. 7 represents an enlarged detail view in perspec-

tive of the spring *h*; and Fig. 8, an enlarged top plan detail view of the base bar *t*.

A fixed horizontal bar *m* of the machine frame is provided with a series of guide rods *g* extending at right angles horizontally therefrom, with intervals between them. Another horizontal bar *m'* of said frame is arranged parallel to bar *m* and considerably above it in the same vertical plane. Rods *g* extend laterally from bar *m'* and correspond in number and position to rods *g* aforesaid.

A carriage *e* runs on each guide rod *g*, carrying a thread-guide *c*, whence the thread passes to a fixed thread-guide *p*, depending from bar *m'*. A curved bobbin-holder base-bar *t* is pivoted at one end on a pivot stud *d* (Figs. 1 and 3) integral with said carriage *e* by means of a hub *t'* (Figs. 4, 5 and 6) having a prismatic lower part *t''*, preferably square in cross section, said hub having a central bore *t³* (Figs. 4 and 6) fitting said stud *d*. The said base bar *t* may be turned from its normal position at will laterally into one at right angles therewith and may be held in either position by the pressure of a leaf brake spring *h*, the latter being fastened to said carriage at one end and bearing by the other end against the face of the prismatic part *t''*, which is presented to said spring, according to the position of said base bar. By turning and holding the said holder out of normal position in this way the exchange of full bobbins for empty ones and the connection of the ends of the threads are facilitated. The carriage *e* may be readily moved along its guide-rod *g* to any point best suited to these operations.

The bobbin-frame comprises besides the curved bar *t*, the straight bobbin-spindles *s*, which are mounted on said bar at such angles that their axes if prolonged would meet at the guide *c*. This is old as above stated, but in addition thereto I have bent the middle part of bar *t* laterally outward as shown in Fig. 2, so as to bring the middle bobbin out of line with the bobbins *b'* *b³* of the series belonging to each bobbin-holder. This construction avoids all risk of injury to the thread from bobbin *b³* by contact with bobbin *b'* when the thread is connected directly between bobbins *b'* and *b³*.

The construction of my bobbin frames and coöoperating parts permits a great number of such frames to be satisfactorily operated within a comparatively small space.

Having thus described my invention, what I claim as new and desire to secure by Letters Patent is:

1. In combination with a guide rod, a carriage movable thereon, a bobbin-holder pivotally mounted on said carriage, bobbins carried by said holder and arranged with converging axes and a thread guide also mounted on said carriage and located at the point of convergence, the thread being connected continuously from bobbin to bobbin of said bobbin-holder and the said pivotal arrangement of the holder being for the purpose of permitting the easy substitution of bobbins and connection of thread as set forth.

2. In combination with a guide rod, a bobbin-holder supported thereon and pivoted for turning laterally at will, a series of bobbins mounted on said holder and provided with continuously connected thread

and means for locking said holder at will in its normal position or in a position at right angles thereto as set forth.

3. A guide rod in combination with a carriage supported thereon and movable along the same, a bobbin holder pivotally mounted on said carriage, a series of bobbins mounted on said holder and provided with connected thread and a spring brake also mounted on said carriage for retaining said bobbin holder at will either in its normal position or in one at an angle thereto for the purpose set forth.

In testimony whereof, I have signed my name to this specification in the presence of two subscribing witnesses.

BERNARD BARTMANN. [L. s.]
